(57) **CLAIM**

I claim a new ornamental design for an oyster opener, as shown and described.

DESCRIPTION

FIG. 1 is a front, top, left side perspective view of an oyster opener showing my new design.

FIG. 2 is a front, top, right side view thereof.

FIG. 3 is a top plan view thereof.

FIG. 4 is a front view thereof.

FIG. 5 is a rear view thereof.

FIG. 6 is a bottom plan view thereof.

FIG. 7 is a left side view thereof.

FIG. 8 is a right side view thereof.

FIG. 9 is a rear, bottom, right side perspective view thereof; and,

FIG. 10 is a rear, bottom, left side perspective view thereof. The broken lines in the disclosure are unclaimed subject matter. The dot-dash lines in FIGS. 61-65 show the boundary between the claimed and unclaimed subject matter.
